CLAIM

USPC **D14/126**

I claim the ornamental design for a display attachment with display device, as shown and described.

DESCRIPTION

(58) **Field of Classification Search**

FIG. 1 is a top, right front perspective view of a display attachment with display device;

USPC D14/371-382, 125-129, 336, 337,

FIG. 2 is a front view thereof;

D14/447-452, 492, 335, 239, 457,

FIG. 3 is a rear view thereof;

D14/439-441, 432, 251-253; D8/349,

FIG. 4 is a left side view thereof;

D8/354, 363, 373, 376, 380; D21/333;

FIG. 5 is a right side view thereof;

D12/415, 175, 345; D3/218; 348/180,

FIG. 6 is a top view thereof;

348/184, 325, 739, 825; 248/124.1,

FIG. 7 is a bottom view thereof; and,

248/125.8, 125.9, 176.1, 411; D6/715.1,

FIG. 8 is a top, right, rear perspective view thereof.
All broken lines in the drawings illustrate portions of the
display attachment with display device that form no part of
the claimed design.
